(57) **CLAIM**

The ornamental design for a microwave grill, as shown and described.

DESCRIPTION

FIG. 1 is a top perspective view of a microwave grill, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of the microwave grill shown in an alternate configuration with the two separable parts combined.

The broken lines in the drawings illustrate the portions of the microwave grill that form no part of the claimed design.
